UNITED STATES PATENT OFFICE

161,643

CATCH BUTTON FOR COMPACTS
OR THE LIKERobert K. Prescott, Elgin, Ill., assignor to Illinois
Watch Case Co., a corporation of Illinois

Application August 26, 1950, Serial No. 11,951

Term of patent 14 years

(CL. D86—10)

To all whom it may concern:

Be it known that I, Robert K. Prescott, a citizen of the United States, residing at Elgin, in the county of Kane and State of Illinois, have invented a new, original, and ornamental Design for a Catch Button for Compacts or the like, of which the following is a specification, reference being had to the accompanying drawing, forming part thereof.

Figure 1 is a top plan view of a catch button, embodying my new design with a representative relative relationship to one form of a compact being illustrated in dotted lines;

Figure 2 is a side view of the catch button and compact illustrated in Figure 1 looking from the bottom of that figure;

Figure 3 is an enlarged plan view of the catch button alone;

Figure 4 is a side view of the button looking from the left of Figure 3;

Figure 5 is an opposite side view of the catch button looking from the right of Figure 3;

Figure 6 is an elevational view of the catch button shown in Figure 3 looking from the bottom of that figure; and

Figure 7 is a bottom view of the catch.

I claim:

The ornamental design for a catch button for compacts or the like, as shown and described.

ROBERT K. PRESCOTT.
